UNITED STATES PATENT OFFICE.

EZRA L. COSGROVE AND WINFIELD SCOTT SMITH, OF WHARTON, OHIO.

COLLAPSIBLE CRATE.

938,041.

Specification of Letters Patent. Patented Oct. 26, 1909.

Application filed May 10, 1909. Serial No. 494,987.

To all whom it may concern:

Be it known that we, EZRA L. COSGROVE and WINFIELD SCOTT SMITH, citizens of the United States, residing at Wharton, in the county of Wyandot and State of Ohio, have invented certain new and useful Improvements in Collapsible Crates; and we do hereby declare the following to be a full, clear, and exact description of the invention, such 10 as will enable others skilled in the art to which it appertains to make and use the same, reference being had to the accompanying drawings, and to the letters of reference marked thereon, which form a part of this 15 specification.

This invention relates to new and useful improvements in collapsible shipping crates and comprises a surrounding wall made up of woven wire and slats and flexible and in 20 the provision of means for holding the crate rigid when opened out.

The invention comprises various details of construction, combinations and arrangements of parts which will be hereinafter 25 fully described and then specifically defined in the appended claim.

We illustrate our invention in the accompanying drawings, in which:—

Figure 1 is a perspective view of a crate 30 made in accordance with our invention. Fig. 2 is a sectional view transversely through the crate and one end thereof, and Fig. 3 is a perspective view showing the crate collapsed.

Reference now being had to the details of the drawings by letter, A, A designate a series of slats forming the surrounding wall or inclosure of the crate, said slats having woven or twisted wires B holding the same 35 spaced apart and securely in place. Said woven or twisted wire is flexible and allows the slats to fold flat, as shown in Fig. 3, when it is desired to economize room for storage or shipment. The ends of the crate 40 are made up preferably of lattice work and certain of the strips C of said ends are extended beyond the ends of the other cross strips forming portions of the ends and are

adapted to engage the corner strips of the surrounding wall or inclosure of the crate 50 and hold the crate rigid by stretching the sides, as will be readily understood. Fixed to each strip C are the metallic angled plates D which project beyond the ends of the strip C and engage over the outer faces of 55 the end of the corner strips of the surrounding inclosure, thereby holding the latter securely in place.

By the provision of a collapsible crate made as shown and described, it will be 60 noted that, when the crate is opened up for use and the end pieces applied thereto, the crate is held rigidly by the provision of the projecting ends of the cross-pieces stretching the sides and in the provision of the angled 65 plates preventing spreading of the walls. When not in use, the ends may be easily removed and the crate reduced to a compact form.

It will be further noted that the circumferential inclosure of the crate is made of a continuous woven work of wire and slats without hinged connections at the corner, the wire to which the slats are fastened being flexible, allowing the crate to fold as 75 well as though the special hinged connections were afforded.

What we claim to be new is:—

A collapsible crate comprising, in combination with a surrounding inclosure made 80 up of woven wire and slats, ends having strips, one of which has projecting ends extending between oppositely disposed slats of the closure, an angled plate upon each projecting end and adapted to engage the outer 85 face of an adjacent slat of the closure and in contact with the woven wire.

In testimony whereof we hereunto affix our signatures in the presence of two witnesses.

EZRA L. COSGROVE.
WINFIELD SCOTT SMITH.
